UNITED STATES PATENT OFFICE.

FRANK H. SOVEREIGN, OF VALLEJO, CALIFORNIA.

UNIVERSAL CLAMPING-TOOL.

1,329,728.

Specification of Letters Patent.

Patented Feb. 3, 1920.

Application filed May 5, 1919. Serial No. 296,643.

To all whom it may concern:

Be it known that I, FRANK H. SOVEREIGN, a citizen of the United States, residing in the city of Vallejo, in the county of Solano 5 and State of California, have invented a certain new and useful Improvement in Universal Clamping-Tools, of which the following is a specification.

My invention relates to tools adapted for 10 rigidly holding stock of a round or other shape during the performance of machine operations upon the stock, and my invention has especial reference to a clamping tool adapted to be attached to the face-plates of 15 lathes, or to the beds or tables of shapers, planers, milling machines and drill presses, in fact, to the work-holding surfaces of any machine tools for the performance of such operations.

20 The objects of my invention are:

First, to provide a base with a block thereon and a jaw slidable in the base and reversible so that the jaw is adapted to hold an object clamped between the block and the 25 jaw at either end of the block.

Second, to provide a clamping tool with 30 means whereby the tool may be secured to the work-holding surface of a machine in such a manner that the bottom surface of the clamping tool either coincides with said 35 work-holding surface or is at a right angle thereto, thus enabling the operator to secure the tool first in one position for the performance of one machine operation upon 40 the object clamped within the tool, and afterward to secure the tool in another position for the performance of another operation, without necessitating readjustment of the object within the clamping tool for the 45 second operation;

Third, to provide a clamping tool with 50 means whereby the tool, in any position wherein it may be secured to the work-holding surface of a machine, is prevented from turning, so that only a minimum of accessories may be required in order to attach the tool to the machine for the performance of operations upon an object clamped within the tool;

55 Fourth, to provide grooves in the block for rigidly holding stock of a round or other shape therein; and

Fifth, to provide a clamping tool which is simple in construction and may be secured

to the work-holding surface of a machine in 55 a minimum space of time.

I accomplish these and other objects, which may appear hereinafter, by means of a device disclosed in the accompanying drawings, which form a part of the present 60 specification and wherein like characters of reference are used to designate similar parts throughout the specification and the drawings, and in which—

Figure 1 is a broken plan view of the 65 work-holding table of a machine tool, and a plan view of my device secured to the table;

Fig. 2 is a side elevation of the device shown in Fig. 1; and a broken end view of 70 the table to which the device is secured, different-sized stock adapted to be held in the different-sized V-grooves, and the splines cut in the stock being shown in dotted lines;

Fig. 3 is a broken plan view of the table, 75 and a view of my device turned on one side and secured to the table, the stock and the splines therein being shown in dotted lines; and

Fig. 4 is an end elevation of my device 80 taken from the right of Fig. 2, and a broken side view of the table to which the device is secured.

Fig. 5 is a longitudinal section taken along 85 the line 5—5 of Fig. 1 in the direction indicated.

My clamping tool comprises a base 1 of a substantially rectangular contour, and upon the top 2 and between the ends 3 and 4 of the base 1 is formed a block 6, the sides 7 and 8 of the block coinciding with the respective sides 9 and 10 of the base, and the ends 11 and 12 of the block being arranged 90 in planes at right angles to the top and the sides of the base. Longitudinally through the base 1, and preferably at one side thereof, is an aperture 14, forming a channel 16 that opens at the top 2 of the base 1 from the end 11 of the block 6 to the end 3 of the base, and another similarly opening channel 17, alined with the channel 16 from the end 12 of the block to the end 4 of the base. 95

Adapted to slide in either of the channels 16 and 17 is a jaw 18, provided with a shank 19 that fits the aperture 14. The shank 19 is internally threaded in order to receive 100 therein the inner end of a stud 21, and the stud has thereupon a nut 22 and a washer, which may be either integral with the nut or

separate therefrom and is adapted to bear with its shoulder 23 against either of the ends 3 or 4 of the base 1 and with its central part 24 to fit in either of the channels 16 or 17 so as to prevent bending of the stud 21 when the nut is tightened.

Upon the bottom surface 26 of the base 1 and extending at a right angle to the sides 9 and 10 of the base, is formed a rib 27, and 10 upon one side of the base, in this instance the side 9, is formed another rib 28, which is alined with the rib 27 and extends from the side 9 to and upon the corresponding side 7 of the block 6 and is at a right angle 15 to the bottom surface 26. It should be understood, however, that a similar rib 28 may also be formed on the side 8 of the block, or the rib 28 on the side 7 may be dispensed with and a similar rib substituted therefor 20 on the side 8, according to the preference of the constructor and according to the purpose for which the clamping tool is to be used, the ribs 27 and 28 being adapted to fit in T-slots 29, formed in the top of a bed or table 25 31 of a machine, not shown, or in the face-plate of a lathe, or in any other work-holding surface of a machine whereto it may be advantageous to attach a clamping tool for the performance of machine operations upon 30 an object secured in the clamping tool. If so desired, the rib 27 on the bottom surface 26 of the base 1 may also be dispensed with, thereby adapting the clamping tool for holding small work during drilling operations and the like, which do not require the 35 securing of the clamping tool to the table of a machine tool.

By means of a nut 32 upon the outer end 40 of a T-bolt 33, fitting in a bore 34 through the block 6, the base 1 and the rib 27 and with its head engaging one of the T-slots 29, the clamping tool may be firmly secured to the bed 31 in the position shown in Figs. 1, 2 and 4, the bore 34 preferably being 45 counterbored, as shown at 36, so that the bolt 33 may be of minimum length and thus only a minimum thereof exposed above the top of the block 6 and the bolt may be out of the way of the machine operations as much as possible. The same or a similar nut 32 and the same or a similar T-bolt 33 may be employed for securing the clamping 50 tool to the bed 31 in the position shown in Fig. 3, the bolt 33 in this instance fitting in a bore 37 that extends through the block 6 from the side 8 to the side 7 and through the 55 rib 28, and the bore 37 being counterbored, as shown at 38, for the same purpose as the bores 34 and 36. While thus secured in the 60 positions shown, to the bed 31, the clamping tool is prevented from turning by means of the respective ribs 27 and 28, so that an excessive strain on the nut 32 and the bolt 33 is unnecessary for holding the clamping tool 65 firmly upon the bed.

For the purpose of securing round stock or other stock of a regular shape within the clamping tool, grooves 41, 42 and 43 may be cut in the ends 11 and 12 of the block 6. These grooves, although shown as V-shaped, 70 may be of any other formation best suitable for holding the stock or other object therein, and the number and arrangement of the grooves may also be varied, according to the nature of the work for which the clamping tool is designed to be used. In the drawings, the groove 41 is shown as being vertically arranged in the end 11 of the block 6, while the groove 42 is horizontally arranged in the same end, and both of these 75 grooves are shown as adapted to receive stock of smaller diameter than the stock adapted to be held in the groove 43, which is shown as being horizontally arranged in the end 12 of the block. Dotted circles 46, 80 47 and 48 suggest the size and the relative position of the stock held in the respective grooves 41, 42 and 43, and the dotted recesses 49 and 50 in the circles 47 and 48, respectively, suggest machine operations, such 85 as the cutting of splines, performed on the stock while held in the grooves 42 and 43, the circle 48 especially indicating how a stock is held in the groove 43, while clamped between the jaw 14 and the block 6, and retained either in a horizontal position, relative to the bed 31, as shown in Fig. 2, or 90 in a vertical position, as shown in Fig. 3.

It is seen from the foregoing that my invention comprises a clamping tool that is 100 of an exceedingly simple construction and is adapted for a great variety of purposes. The usefulness of the tool is especially increased by the reversibility of the jaw 18, whereby an object may be clamped within 105 the clamping tool at either end of the block 6, it being necessary for changing the jaw from the channel 17, in which it is shown in the drawings, to the channel 16 only to remove the nut 22 and its washer from the 110 stud 21, whereafter the shank 19 and the jaw 18 may be inserted in the channel 16 and by means of the nut 22 the jaw can be moved toward the end 11 of the block 6 in order to 115 secure, for instance, the stock 46 in the vertical V-groove 41, or the stock 27 in the horizontal V-groove 42.

My invention being thus fully and clearly described, what I claim as new and desire to 120 secure by Letters Patent, is:

1. In a clamping tool, the combination with a base having a substantially rectangular contour, of a block on the top and between the ends of the base, the sides of the block coinciding with the sides of the base; an aperture longitudinally through the base, the aperture forming alined channels from the ends of the block to the ends of the base; a clamping jaw provided with a shank fitting the aperture, said jaw being adapted to 125

slide in either of the channels; and means engaging the shank and the base for holding an object clamped between the jaw and the block.

5 2. In a clamping tool, the combination with a base having a substantially rectangular contour, of a block on the top and between the ends of the base, the sides of the block coinciding with the sides of the base; 70
10 an aperture longitudinally through the base, the aperture forming alined channels from the ends of the block to the ends of the base; a clamping jaw provided with a shank fitting the aperture, said jaw being adapted 75
15 to slide in either of the channels; and means engaging the shank and the base for holding an object in one of the grooves clamped between the jaw and the block.

15 3. In a clamping tool, the combination with a base having a substantially rectangular contour, of a block on the top and between the ends of the base, the sides of the block coinciding with the sides of the base; 80
20 a rib formed on the bottom surface of the base and extending at a right angle to the sides of the base; and a bore through the block, the base and the rib.

25 3. In a clamping tool, the combination with a base having a substantially rectangular contour, of a block on the top and between the ends of the base, the sides of the block coinciding with the sides of the base; 85
30 an aperture longitudinally through the base, the aperture forming alined channels from the ends of the block to the ends of the base; a clamping jaw provided with a shank fitting the aperture, said jaw being adapted 90
35 to slide in either of the channels; means engaging the shank and the base for holding an object clamped between the jaw and the block; a rib formed on the bottom surface of the base and extending at a right angle to the sides of the base; and a bore through the block, the 95
40 base and the rib.

4. In a clamping tool, the combination with a base having a substantially rectangular contour, of a block on the top and between the ends of the base, the sides of the 100
45 block coinciding with the sides of the base; an aperture longitudinally through the base, the aperture forming alined channels from the ends of the block to the ends of the base; a clamping jaw provided with a shank fitting the aperture, said jaw being adapted to slide 105
50 in either of the channels; means engaging the shank and the base for holding an object clamped between the jaw and the block; a rib extending on one side of the base and the corresponding side of the block and at a right angle to the bottom surface of the base; and a bore extending through the block from one side thereof to the other and through the rib. 110
55

5. In a clamping tool, the combination with a base having a substantially rectangular contour, of a block on the top and between the ends of the base, the sides of the 115
60 block coinciding with the sides of the base; grooves in the ends of the block; an aperture longitudinally through the base, the aperture forming alined channels from the ends of the block to the ends of the base; a clamping jaw provided with a shank fitting the aperture, said jaw being adapted to slide 120
65 in either of the channels; means engaging the shank and the base for holding an object clamped between the jaw and the block; a rib at the bottom of the base; and a second bore extending through the block from one side thereof to the other and through the rib at the side. 125

65 5. In a clamping tool, the combination with a base having a substantially rectangular contour, of a block on the top and between the ends of the base, the sides of the block coinciding with the sides of the base; 70
70 grooves in the ends of the blocks; an aperture longitudinally through the base, the aperture forming alined channels from the ends of the block to the ends of the base; a clamping jaw provided with a shank fitting the aperture, said jaw being adapted to slide 75
75 in either of the channels; and means engaging the shank and the base for holding an object in one of the grooves clamped between the jaw and the block.

6. In a clamping tool, the combination with a base having a substantially rectangular contour, of a block on the top and between the ends of the base, the sides of the block coinciding with the sides of the base; 80
80 grooves in the ends of the block; an aperture longitudinally through the base, the aperture forming alined channels from the ends of the block to the ends of the base; a clamping jaw provided with a shank fitting the aperture, said jaw being adapted 85
85 to slide in either of the channels; and means engaging the shank and the base for holding an object in one of the grooves clamped between the jaw and the block.

6. In a clamping tool, the combination with a base having a substantially rectangular contour, of a block on the top and between the ends of the base, the sides of the block coinciding with the sides of the base; 90
90 grooves in the ends of the block; an aperture longitudinally through the base, the aperture forming alined channels from the ends of the block to the ends of the base; a clamping jaw provided with a shank fitting the aperture, said jaw being adapted 95
95 to slide in either of the channels; means engaging the shank and the base for holding an object in one of the grooves clamped between the jaw and the block; a rib formed on the bottom surface of the base and extending at a right angle to the sides of the base; and a bore through the block, the base and the rib.

7. In a clamping tool, the combination with a base having a substantially rectangular contour, of a block on the top and between the ends of the base, the sides of the block coinciding with the sides of the base; 100
100 grooves in the ends of the block; an aperture longitudinally through the base, the aperture forming alined channels from the ends of the block to the ends of the base; a clamping jaw provided with a shank fitting the aperture, said jaw being adapted to slide 105
105 in either of the channels; means engaging the shank and the base for holding an object in one of the grooves clamped between the jaw and the block; a rib extending on one side of the base and the corresponding side of the block and at a right angle to the bottom surface of the base; and a bore extending through the block from one side thereof to the other and through the rib. 110
115

8. In a clamping tool, the combination with a base having a substantially rectangular contour, of a block on the top and between the ends of the base, the sides of the block coinciding with the sides of the base; 120
120 grooves in the ends of the block; an aperture longitudinally through the base, the aperture forming alined channels from the ends of the block to the ends of the base; a clamping jaw provided with a shank fitting the aperture, said jaw being adapted to slide 125
125 in either of the channels; and means engaging the shank and the base for holding an object in one of the grooves clamped between the jaw and the block.

shank and the base for holding an object in one of the grooves clamped between the jaw and the block; a rib formed on the bottom surface of the base and extending at a right angle to the sides of the base; a second rib alined with the first rib and extending on one side of the base and the corresponding side of the block and at a right

angle to said bottom surface; a bore through the block, the base and the rib at the bottom of the base; and a second bore extending through the block from one side thereof to the other and through the rib at the side.

In witness whereof I hereunto set my signature, this 26th day of April, A. D. 1919. 15

FRANK H. SOVEREIGN.
